UNITED STATES PATENT OFFICE.

WILLIAM NELSON AND EUGENE BOWEN, OF TOMOANA, NEW ZEALAND.

WOOL-DRYING APPARATUS.

SPECIFICATION forming part of Letters Patent No. 394,713, dated December 18, 1888.

Application filed May 14, 1888. Serial No. 273,894. (No model.) Patented in New Zealand June 11, 1887, No. 2,381; in Tasmania July 23, 1887, No. 476/9; in Victoria August 25, 1887, No. 5,265; in England August 27, 1887, No. 11,665; in New South Wales August 27, 1887, No. 148, and in Queensland September 26, 1887, No. 324.

To all whom it may concern:

Be it known that we, WILLIAM NELSON and EUGENE BOWEN, citizens of the colony of New Zealand, both residing at Tomoana, in

5 the provincial district of Hawke's Bay, in the said colony, and subjects of Her Majesty Queen Victoria, have invented a new and useful Improved Machine for Drying Wool, (for which we have obtained the following patents: 10 New Zealand, No. 2,381, bearing date June 11, 1887; Tasmania, No. 476/9, bearing date July 23, 1887; Victoria, No. 5,265, bearing date August 25, 1887; Great Britain, No. 11,665, bearing date August 27, 1887; New South 15 Wales, No. 148, bearing date August 27, 1887, and Queensland, No. 324, bearing date September 26, 1887,) of which the following is a specification.

The objects of our invention are to expose 20 the wool to be dried to a current of warm air, so that its fibers may be repeatedly acted upon by such air, and thus be regularly and rapidly dried, and to expel the dried wool from the machine by means of a blast or current of 25 air.

Our improved machine consists of a drum open at both ends and revolving in a casing, the cylindrical portion of the said drum being constructed of bars and annular bands, 30 between which bars air is forced from a longitudinal air-trunk in the said casing. The interior of the drum is furnished with longitudinal shelves, which, as the drum revolves, successively take up portions of the wool and 35 allows them to fall, and thus expose them fully to the current of air. The dried wool is ejected from the machine by means of a current of air diverted from the air-trunk and forced through a pipe opening into the feed 40 end of the drum.

Having thus described the nature of our invention, we will proceed to describe the manner in which the same is to be performed, reference being had to the accompanying 45 drawings, and to the letters and figures marked thereon.

Figure 1 represents the machine partly in side elevation and partly in section, taken on the line YZ, Fig. 2. Figs. 2 and 3 respectively 50 represent the feed and discharge ends of the

drum. Fig. 4 represents in section, on a larger scale, one of the panels hereinafter described; and Fig. 5 represents the air-trunk in cross-section on a larger scale.

The same letters indicate the same parts in 55 all the figures.

A A is the casing of the machine.

B is the drum, the ends of which are formed of wooden rings b' b', made in segmental portions or fellies screwed together, the said rings 60 being strengthened with iron bands or wires b² b², which run upon friction-rollers c' c' c' c', the roller c' being grooved, as shown. The drum may be driven from either end by means of a belt passing from one of the rings b' b' 65 to a driving-pulley overhead. Inside flanges, b³ b³, are affixed to the rings b' b', the said flanges being strengthened by means of iron rings b⁴ b⁴, which also form seatings for the doors D' D². The door D' is hinged to the 70 bar d' and the door D² is hinged to the bar d², the latter being secured at its ends to casting A.

b⁵ b⁵ are tubes screwed to the rings b' b', and extending from end to end of the drum. The 75 spaces between these tubes are filled by longitudinal panels of wooden bars b⁶, Figs. 1, 3, and 4, forming the periphery of the drum, narrow spaces being left between the bars for the passage of the air. The said bars b⁶ are 80 held by notched segments b⁷. (See Fig. 4.)

E E are shelves consisting of curved iron bars e' e', to which are screwed cylindrical wooden bars e² e². Those portions of the bars e' e' to which the bars e² e² are screwed 85 have curved hollows filed therein to receive the said bars e² e², and the portions which pass through the tubes b⁵ b⁵ are turned smaller than the other portions and have screw-threads and nuts by which they are bolted 90 to the said tubes. In constructing the drum the tubes b⁵ b⁵, with the shelves E E affixed thereto, are screwed to the rings b' b', and the panels b⁶ b⁶ are successively placed between the said tubes and fixed in position 95 by strips of iron banding b⁸ b⁸, in which are drilled holes coinciding with the holes in the tubes b⁵ b⁵, through which are passed the screw-bolts which secure the strips to the said tubes.

F is an air-trunk, into which warm air is forced through the main trunk H by a fan or other suitable blowing apparatus. The air-trunk F is fixed in one of the lower angles 5 of the casing A and has a longitudinal slit, f', forming a discharge-orifice for the air, which passes between the bars b⁶ b⁶ into and obliquely through the drum to a longitudinal opening, a', near the opposite upper angle of 10 the said casing, through which the heated air escapes from the machine. The course of the said air is indicated by the arrows.

G is a pipe, the bent end of which projects through the casing into the drum, through 15 which pipe air is forced into the drum for the purpose of blowing the dried wool out of it, and thus rapidly emptying the said drum. The lower end of the pipe G opens into the main trunk H.

20 By referring to Fig. 3 it will be seen that as soon as each of the shelves E E has passed its highest point of revolution the blast of air is directed upon the dried wool just as it is falling from the shelf.

25 h' is a flap-valve mounted on a spindle, h², turned as required by a handle, h³, which can be hooked to the casing A, so as to keep the said valve either in its vertical or horizontal position. When the valve is horizontal,

30 it closes the communication between the main trunk H and the pipe G and admits the current of air to the air-trunk F, and when the said valve is vertical it shunts the air from the air-trunk F into the pipe G.

35 a² a² are doors for the removal of the dust which is shaken out of the wool.

Although we have represented our machine as made chiefly of wood, it may be made of galvanized iron or other suitable material.

40 Two or more of our machines may be arranged side by side, in which case the air-trunks thereof receive their supply of air from the main trunk H, common to all.

The action of the machine is as follows: 45 The workman first starts the drum and fixes the valve h' in its horizontal position, and thus directs the current of warm air into the air-trunk F. He then throws the wet wool to be dried into the drum through the feed end 50 thereof and closes the door D'. As the drum revolves, the shelves E E carry up portions of the wool, which fall from the said shelves as they pass their highest point of revolution. The fibers are thus repeatedly exposed to the 55 current of warm air passing upward from the air-trunk F until they are dried, and are also freed from the greater part of any dust, &c., which they may contain, and which, being shaken out by the action of the drum, falls

through the bars thereof onto the floor, from 60 which it can from time to time be removed through the doors a² a². When the wool has been sufficiently dried, the workman opens the door D² and fixes the valve h' in its vertical position, and thus diverts the air from 65 the air-trunk F to the pipe G, whence it issues with sufficient force to expel the dried wool from the drum as the said wool falls from the shelves E E. He then, without stopping the drum, closes the door D', opens the door D², 70 fixes the valve h' in its horizontal position, throws in more wet wool, and the operation is repeated.

We have found in practice that six revolutions a minute is a good speed at which to 75 drive the drum, and that a blast of air at a temperature of from 96° to 100° Fahrenheit gives a good result; but we do not limit ourselves either to the speed or the heat described. 80

Having now described the nature of our invention and the manner in which the same is to be performed, we wish it to be understood that we do not limit ourselves to the precise details hereinbefore described, as they may 85 be varied without departing from the nature of our said invention; but

We claim as our invention—

1. In a wool-drying machine, the combination of the outer casing, the drum mounted to 90 revolve therein and having open ends, its periphery being formed by bars with intermediate spaces for the passage of air, the inwardly-projecting shelves for raising the wool to the top of the drum and then permitting it 95 to fall, an air-trunk having a longitudinal slit or orifice, and a pipe leading from said air-trunk and communicating directly with said drum through the feed end thereof for the purpose of discharging the contents thereof, 100 substantially as described.

2. The combination of the outer casing, the revolving drum having open ends and spaces in its periphery for the admission and exit of air, a longitudinal air-trunk within said casing and having a discharge-orifice below said drum, doors at the ends of said drum, a pipe leading from the air-trunk to the feed end of the drum, and a valve for controlling the direction of the air-current, substantially as described. 110

WILLIAM NELSON.
EUGENE BOWEN.
